United States Patent Office.

EDWIN CLARK, OF LANCASTER, PENNSYLVANIA.

Letters Patent No. 64,074, dated April 23, 1867.

IMPROVED WINDOW-SASH FRAME.

The Schedule referred to in these Letters Patent and making part of the same.

TO ALL WHOM IT MAY CONCERN:

Be it known that I, EDWIN CLARK, of the city and county of Lancaster, in the State of Pennsylvania, have made a new and useful improvement in Window-Sashes and Frames; and I do hereby declare the following to be a full and exact description of the same, reference being had to the accompanying drawings, making part of this specification, and in which—

Figure 1 is a vertical section of a window-frame and sashes, showing my improvement.

Figure 2 is a vertical section, showing the manner of attaching the strip which holds the sash in place.

Figure 3 is a detached sectional view of the manner of attaching the sash to the sliding strip.

Figure 4 is a transverse horizontal section through the left side of the window-frame; and

Figure 5 is a detached sectional view, showing the manner of attaching the weighted rope to the sash.

Similar letters of reference indicate corresponding parts in the several figures.

The nature of my invention consists in providing novel means to take the window-sashes out from the frame, so as to prevent the necessity of standing on the window-sill on the outside of the upper stories of buildings, which is now the common practice of servants when washing the windows, or of painters when re-painting sashes.

To enable others skilled in the art to which my invention appertains to fully understand and use the same, I will now proceed to describe its construction and operation.

A, in my drawings, may represent the frame of a window, and B the upper, and B¹ the lower sash of the same. The left upright piece of the lower sash B¹ is constructed of two pieces, b and b¹, the piece b¹ of the sash being provided with a groove, c, sliding over an inclined tongue, d, on the piece b. The widest part of this tongue is at its top, and is provided with a hook-shaped projection, d¹, which catches under a slot, c¹, in the groove c of the piece b¹. At the lower end of the tongue d is fastened a straight spring, d², which catches under the eye c² in the groove c. When the piece b¹ is slid on the piece b, the projection d¹ glides into the slot c¹, the eye c² over the spring d², and the inclined face of the tongue forces the two pieces b and b¹ closely together. But as the wood in the sash is likely to shrink or expand with the changes in the weather, which would either allow the window to rattle or tighten the tongue so in the groove that it would be difficult to separate them, I prefer the use of two springs on a straight tongue, which, if the wood shrinks, will draw the two pieces together and hold them firmly to each other, or, as the wood expands, will gradually give with the wood, so that the sash-frame will always be perfectly air-tight, and the two pieces b and b¹ can still be separated with perfect ease. In the upper part of the outer edge of the piece b, as well as on the corresponding part of the other upright of the lower sash, and the corresponding parts of the upper sash, are formed grooves, e, to hold the weighted ropes f, by means of which the sashes are raised and lowered. These grooves terminate in a groove, e¹, running upwardly, which catches and securely holds the knots of the rope f. I am aware that grooves have been used for this purpose, provided at their lower ends with a hollow place for the knot to lie in, out of the way of the sliding of the sash, but in these cases the employment of metal plates is necessary to hold the rope in place, whilst by means of my peculiar shaped groove, e e¹, I am enabled to dispense with any other fastening for the ropes, and to readily attach the sash to the ropes or detach it from them. The sashes are held in place by and slide between the inner strip g, the centre strip h, and the projecting part i of the frame A. The strip h is removable, fitting in a groove in the frame A. The strip g is also similarly removable, and is provided with three eyes, g¹, through which pins, j, pass from the inner side of the frame far enough to pass into holes in the strips h in such a manner that the pins j hold both strips at once. Though it is not necessary, still I prefer to make the strip g with a tongue, g², fitting into a corresponding groove in the groove into which the strip g fits, and to which tongue, g², the eyes g¹ are secured. By this arrangement I gain additional security against the shaking loose of the strip g when the window is shaken by the wind and storm, and prevent the rattling of the same. I provide the pins with fancy heads, so that they shall be an ornament to the frame.

Operation.

To remove the lower sash alone, I place a pin, which for that purpose may always be kept in a separate hole in the frame A, into the hole k, which passes through the strip g into but not through the piece b. This pin holds the latter firmly in place, whilst by raising the sash the same will be separated from it, the slot c¹ sliding from the projection d¹, the eye c² from the spring d², and the groove c from the tongue d. As soon as

the groove c is clear from the tongue d , that side of the sash can be swung out, which will enable the other side to be removed from its groove. The rope can be detached by simply taking it out of the groove c^1 , and may be fastened to a pin placed in the frame for that purpose, or may be allowed to run up to the roller, where it will be held by the knot, and the sash is detached from the frame and can be taken anywhere to be cleaned or painted. To take out the upper sash, I withdraw the pin holding the piece b from the hole k , which allows the same to be taken off the rope, and take out the three pins j , thus at once freeing both strips g and h , which, when removed from the grooves in the frame in which they are held, leave one side of the sash clear from the frame and easy to be taken out, when the ropes are detached and the sash can be taken away. To replace the sashes, I first attach the ropes of the upper sash by simply placing them in the grooves c , the knots resting in the parts c^1 . I then replace the sash in its proper position and replace the strip h . I then attach the piece b to the part b^1 of the lower sash by sliding the groove c over the tongue d , the slot c^1 slipping over the projection d^1 , and the eye c^2 over the spring d^2 , replace the ropes in the grooves and the sash into its place, when by returning the strip g into the corresponding groove in the frame A, and pushing the pins j through the same and the eyes g^1 into the strip h , the whole is again securely fastened. To simply remove and replace the lower sash, I need not remove either the pins j or the strips g and h . I remove it as described above, and in replacing it merely place the solid upright of the sash into its corresponding groove in the frame A, and the groove c over the tongue d , when by pushing the sash down it fastens itself to piece b , as described. By removing the pin from the hole k the sash is again free to be operated, the weight of the sash, combined with the action of the inclined face of the tongue d , the projection d^1 , and the slot c^1 , and the spring d^2 and eye c^2 , keeping the pieces b and b^1 firmly attached to each other.

I am aware that it is not new to make one or both of the upright pieces of a sash in two parts, they having been so constructed that the two pieces are held together by means of a catch on the inside of the sash, which, when accidentally broken or loosened, would permit the sash to fall from its place, there being nothing to prevent its coming out laterally in case of such an accident. But by my invention I can not only as easily detach the sash, but when not detached keep it in place as strongly and securely as any sash the uprights of which are made undivided.

Having thus described my invention, what I claim as new therein, and desire to secure by Letters Patent, is—

1. The inclined tongue d and corresponding groove c on the pieces b and b^1 , respectively, of a window-sash, substantially as and for the purposes described.
2. The projection d^1 on the inclined tongue d , slots c^1 , springs d^2 , and eyes c^2 , on the pieces b and b^1 , respectively, of a window-sash, substantially as and for the purposes described.
3. The eyes g^1 on the strips g and pins j , passing through the same and the window-frame, substantially as described.
4. The tongue g^2 on the strip g , and corresponding groove in the frame A, substantially as and for the purposes specified.
5. The above-described mode of removing and replacing window-sashes from frames, substantially as and for the purposes specified.

The above specification of my improvement in window-sashes and frames signed this 19th day of February, 1867.

EDWIN CLARK.
